ROTARY MULTICOLOR PRINTING MACHINE

Robert Thomas Colville, Chelsea, Victoria,
AustraliaApplication August 16, 1933, Serial No. 685,449
In Australia August 30, 1932

5 Claims. (Cl. 101—177)

This invention relates to rotary multi-color printing machines and its object is to provide an improved machine whereby printed matter may be produced in a plurality of colors more rapidly than with known machines, at reduced cost, and with the several colors in accurate register.

A further object of this invention is to avoid the disadvantages which are associated with the release and partial delivery of a sheet before printing is completed.

A still further object of this invention is to provide a machine in which perfecting may be effected in one, two or more colors on both sides of a sheet simultaneously.

15 A feature of this improved machine is that printed sheets may be delivered face upward without the aid of wheels, discs or other devices and in such manner that no part of the machine will contact with the wet printed matter.

20 This invention is characterized in that the impression cylinder has a plurality of faces not less than three and in that in each revolution each sheet carrying face is preceded and followed by a face which is blank in that revolution.

25 This invention is further characterized in that when the impression cylinder has an odd number of faces the face which carries a sheet which is being printed is followed by a blank face and is preceded by a face which is blank until it receives a sheet to be printed during the next revolution, and in that the said sheet carrying face becomes a blank face in the said next revolution.

30 This invention is further characterized in that when the impression cylinder has an even number of faces alternate faces are permanently blank.

35 This invention is further characterized in that each cylinder which is adapted to revolve in contact with the impression cylinder has alternate operative faces and blank spaces and in that during ordinary offset or direct printing each operative face is adapted to contact with a sheet carrying face on the impression cylinder and each blank space registers with a blank face on the impression cylinder.

40 This invention is further characterized in that during perfecting the face which is to carry a sheet in the next revolution receives an impression from a co-operating cylinder which will be offset on to the inner face of said sheet when its outer face receives an impression from another co-operating cylinder during said next revolution.

45 In the present embodiment of this invention the impression cylinder has an odd number of faces, not less than three, and each co-operating

cylinder associated with it has one face the same size as an impression face, and a space equal to the distance between alternate impression faces.

In a modified arrangement the impression cylinder has an even number of faces, not less than 5 four and alternate faces are permanently blank.

But in order that this invention may be more readily understood it will now be described with reference to the accompanying drawings in which only the main cylinders are diagrammatically illustrated, the inking rollers, tripping mechanism and other machine parts being omitted.

Fig. 1 shows parts of a multi-color offset printing machine comprising an impression cylinder having three impression faces two co-operating 10 offset cylinders and two printing cylinders associated with each offset cylinder.

Fig. 2 is a similar view to Fig. 1 but showing the position of the parts after the impression cylinder has revolved one third of a revolution 15 from the position shown in Fig. 1.

Fig. 3 is a similar view to Fig. 1 but adapted for perfecting in two colors simultaneously on each side of a sheet.

Fig. 4 is a similar view to Fig. 3 but showing 25 the position of the parts after the impression cylinder has revolved one third of a revolution from the position shown in Fig. 3.

Fig. 5 is a similar view to Fig. 1 but with an impression cylinder having five faces.

Fig. 6 is a similar view to Fig. 1 but showing an impression cylinder having two impression faces and two blank faces.

Fig. 7 shows parts of a direct multi-color printing machine which includes an impression cylinder having five faces combined with four printing cylinders.

Fig. 8 shows parts of a machine similar to that shown in Fig. 1 but with the offset cylinders and the printing cylinders arranged so that they may 40 be adjusted relatively to driving gear, for perfecting.

Fig. 9 is a similar view to Fig. 8 but with the right hand offset cylinder and the associated plate cylinders adjusted for perfecting.

Fig. 10 is an end view of an adjustable cylinder.

Fig. 11 is a vertical central section of the parts shown in Fig. 10.

In the drawings, 11 is the impression cylinder, 50 and in Figs. 1 to 6, 12 and 12^a are co-operating offset cylinders, 13, 13^a are plate cylinders associated with offset cylinder 12, and 13^b, 13^c are plate cylinders associated with offset cylinder 12^a. The said parts may be combined in a machine 55

in any known manner with means whereby they may be revolved in unison. Such means and other essential well known parts may be of any suitable construction, combined and arranged in manner well known to printing machine engineers. It will be obvious that more than two offset cylinders may be employed and also that means may be provided whereby matter to be printed may be deposited in more than two colors on each or any selected offset cylinder.

In Figs. 1 to 4, cylinder 11 has three impression faces 11^a, 11^b and 11^c of similar size while in Figs. 5 and 7 the impression cylinder has five faces, the two additional faces being marked 11^d, 11^e. The said impression faces are spaced apart only a sufficient distance to permit operation of gripper mechanism of well known form (not shown) which co-operates with the leading edge of each impression face to locate a sheet of material. In Fig. 6 the impression cylinder has four faces two of which, 11^f and 11^g, are operative, while the alternate faces 11^h and 11ⁱ are permanently blank and inoperative.

Each cylinder 12 and 12^a (Figs. 1 to 6) has one offset face 12^b the dimensions of which correspond to the dimensions of each impression face and each said face 12^b carries an offset blanket 12^d of suitable material such as rubber or rubber composition. The space 12^c, on each offset cylinder is blank, and is complementary circumferentially with the space between alternate faces of the impression cylinder.

Each printing cylinder 13 to 13^c has a plate carrying face 13^d which corresponds in dimensions with the face 12^b on the offset cylinder with which it is associated. The remaining portion 13^e of each printing cylinder is blank and is complementary to space 12^c.

Any suitable feed and delivery means is usable and such means may be located at any suitable position. By way of example feed means as 15 and delivery means as 14, which are suitable for paper, are illustrated in Figs. 1 to 5 and Fig. 7 but the position of such means may be varied to suit sheets of other material such as cardboard and tin, as shown at 14^a and 15^a respectively in Fig. 6.

In the form shown in Fig. 7 the impression cylinder has five faces 11^a to 11^e but the offset cylinders are omitted the co-operating cylinders being printing cylinders 13^c each of which has a plate carrying face 13^d which contacts directly with the paper carrying impression faces in each revolution, the blank space 13^h on each cylinder 13^c registering with impression faces which are blank in that revolution.

Referring now to Fig. 1, assuming that face 11^b which is shown in contact with cylinders 12, 12^a, is carrying a sheet of paper or other material S¹, the matter to be printed which has previously been deposited by the plates on faces 13^d on to blankets 12^d, is now being offset from said faces on to the said sheet.

During this revolution face 11^a (that is the face preceding face 11^b) is blank and so also is face 11^c which has just delivered a sheet S². When the leading edge of face 11^a reaches the feed means 17 it commences to receive a sheet S³ but the rear portion of face 11^a remains blank until the sheet on face 11^b is completely printed. Assuming now that the cylinder 11 turns one third of a revolution, that is from the position in Fig. 1 to that in Fig. 2, face 11^a carrying sheet S³ revolves toward the printing position preceded by face 11^c which is still blank and the

printed sheet S¹ carried by face 11^b is approaching the point at which it will be delivered so that while the sheet on face 11^a is being printed it is preceded and followed by a face which is blank in that revolution. When face 11^c reaches the feed point 17 it commences to receive a sheet and the cycle of operations continues as before described.

With an impression cylinder having five faces the cycle of operations is the same as before described in that the sheet carrying face is preceded and followed by a face which is blank in that revolution. In Fig. 5, S⁴ is a printed sheet approaching the delivery point, S⁵ a sheet which is being printed and S⁶ a sheet to be printed.

In each case the sheet carrying face in one revolution is blank in the next revolution and each face which is blank in that revolution becomes a sheet carrying face in a succeeding revolution.

When perfecting on both sides of a sheet is to be effected simultaneously, one of the offset cylinders (for example cylinder 12^a) is turned through 180° and the printing cylinders associated with it are similarly adjusted (see Figs. 3 and 4) and each face of the impression cylinder 11 is provided with an offset blanket 16. The effect of this is that in each revolution the blank faces preceding and following the sheet carrying face each contact with blankets 12^d of cylinder 12^a and matter to be printed on the inner side of a sheet is deposited thereon so that during the next revolution, when such face is carrying a sheet, it meets the blanket 12^d of cylinder 12 and receives matter therefrom in its outer face, the pressure resulting also in the transfer of the impression from the blanket 14 on to its inner face so that perfecting is effected on both sides simultaneously.

In Fig. 3 S¹ is a sheet being printed, S² a sheet which has just been delivered and S³ a sheet to be printed as already described with reference to Fig. 1 the sheets in Fig. 4 being in the same positions as in Fig. 2.

To enable an offset cylinder and its associated plate cylinders to be adjusted as described, each said cylinder is connected to its driving gear 18 by bolts 19 which are located at accurately spaced apart intervals. When the machine is to be used for perfecting the bolts 19 which hold one offset cylinder (12^a for example) and its associated plate cylinders are removed, and the said cylinders are turned through 180 degrees relatively to their respective gears 19, that is from the position shown in Fig. 8 to that shown in Fig. 9 and the bolts 19 are positioned to secure the respective cylinders in their adjusted positions.

The form shown in Fig. 6 is particularly suitable for relatively stiff material such as sheets of tin or card. In this case as each impression face is separated by a permanently blank space and each said face is adapted to receive and deliver a sheet in each revolution, thus as illustrated face 11^b is carrying a sheet S⁷ to be printed while face 11^f has just dropped a printed sheet S⁸ and is approaching the feeder to receive another sheet S⁹.

I claim:—

1. In a multi-color printing machine, a main frame, an impression cylinder rotatably mounted therein, an odd plurality of impression faces on said cylinder, an offset blanket on each said face at least two offset cylinders operatively mounted in relation to the said impression cylinder, each said offset cylinder having an offset face and a

space the arrangement being such that the offset face contacts with alternate impression faces, a plurality of plate cylinders mounted in operative contact with each offset cylinder, and means whereby an offset cylinder and associated plate cylinders may be circumferentially adjusted so that in each revolution each face of the impression cylinder which does not carry a sheet in that revolution receives an impression which is offset 10 on to the inner face of a sheet when the outer face of said sheet receives an impression from another offset cylinder in the following revolution.

2. In a multi-color offset printing machine, a main frame, an impression cylinder rotatably mounted therein, an odd plurality of impression faces on said impression cylinder, at least two offset cylinders operatively mounted in relation to the said impression cylinder, an offset face and a space on each offset cylinder, the arrangement being such that the offset face contacts with alternate impression faces, an offset blanket on each face of the impression cylinder and means whereby one or more of said offset cylinders may be adjusted circumferentially so that when an 25 offset face of one offset cylinder is printing on a sheet carrying face of the impression cylinder, the circumferentially adjusted offset cylinder will contact with faces which precede and follow a sheet carrying face and which do not carry a sheet in that revolution.

3. In a multi-color offset printing machine, a main frame, an impression cylinder rotatably mounted therein, an odd plurality of impression faces on said cylinder, at least two offset cylinders operatively mounted in relation to the said impression cylinder, each said offset cylinder

having an offset face and a space, the arrangement being such that the offset face contacts with alternate impression faces, an offset blanket on each face of the impression cylinder and means whereby any selected offset cylinder may be circumferentially adjusted so that in each revolution each non-sheet carrying face on the impression cylinder receives an impression which will be offset on to the inner face of a sheet in the following revolution.

4. A multicolor offset printing machine comprising fixed framing, a rotatable impression cylinder, an odd plurality of faces on said impression cylinder, means to feed material to receive an impression to each alternate face of the impression cylinder in each revolution, a plurality of rotatable offset cylinders, an offset face and a space on each offset cylinder the said offset face and space being so arranged that in each revolution the offset face registers with an impression face and the space registers with the impression face in advance of and the impression face at the rear of the registering impression face, and a plurality of plate cylinders co-operating with each offset cylinder.

5. In a multicolor offset printing machine as claimed in claim 4, an offset blanket on each face of the impression cylinder, and means whereby one of the offset cylinders and the plate-cylinders associated therewith may be adjusted relatively the impression cylinder so that the offset face of the said offset cylinder deposits an impression directly on the blanket of each impression face which registers with the space of the other offset cylinder in that revolution.

ROBERT THOMAS COLVILLE.
